UNITED STATES PATENT OFFICE.

CHARLES DONAGHY, OF PHILADELPHIA, PENNSYLVANIA.

BRUSH-HANDLE.

SPECIFICATION forming part of Letters Patent No. 330,005, dated November 10, 1885.

Application filed August 11, 1884. Serial No. 140,512. (No model.)

To all whom it may concern:

Be it known that I, CHARLES DONAGHY, of the city and county of Philadelphia, and State of Pennsylvania, have invented an Improvement in Handles, of which the following is a specification.

My invention has reference to handles for brushes, tools, &c.; and it consists in certain improvements whereby the handle is detachably secured to the article to be held, all of which is fully set forth in the following specification and shown in the accompanying drawings, which form part thereof, and particularly pointed out in the claim.

15 The object of my invention is to provide a suitable handle for whitewash and other brushes, tool-handles, &c., which shall be readily secured and detached therefrom, as desired, at the same time forming a most rigid and durable connection.

The state of the art may be briefly stated as follows: Brush and broom handles were made in sections and detachably secured together and also to the brush—for instance, in the 25 patent to Mueller, No. 259,901, is shown a construction for attaching the handle to a carpet-sweeper, in which the iron holding the sweeper proper is provided with several spurs which are forced into the bottom of the wooden 30 handle to prevent it from turning, and said handle is then secured in place by an ordinary wood-screw passing through the iron into the handle. In the patent to Light, No. 159,105, is shown a jointed brush-handle, the two parts 35 being secured in line and attached by a double socket-piece provided with screws upon which the wooden sections of the handle are screwed. In the patent to Herr, No. 53,923, is shown a fountain-brush, in which a tubular handle 40 forms a reservoir, and a brush-carrying section is drawn up into said handle by a screw, insuring the positive flow of liquid to the brush; but in no sense is this a positive connection, such as contemplated in my construction. All of these devices, while more or less 45 similar in some respects, are very different in specific construction from that sought to be claimed in this application, one of the essential features of my construction being the 50 metal socket-piece E' when forced down into the end of the wooden handle, the lower end of which is inclosed in a metal ferrule, and

the screw D', which is secured to the brush or other article to be held, made to screw into the metal socket-piece E', and not into the perishable wood.

In the drawings, Figure 1 is a side elevation of a handle and brush complete embodying my improvements. Fig. 2 is a sectional elevation of the connection between the handle proper and brush-support. Fig. 3 is a similar section of the coupling for uniting two sections of the handle. Fig. 4 is a front elevation of one form of metal frame to which the brush is secured. Fig. 5 is a perspective view of another form of same, and Fig. 6 is a side elevation showing my invention as applied to a soldering-iron.

A is the main handle, and A' are the sections, of which there may be any number desired. The upper end of handle A is fitted with a screw-threaded socket-piece, E, driven down into a hole, or otherwise secured therein. The lower end of the next section, A', is provided with a double-cup-shaped piece, C, having the cups C' pointing in opposite directions from the diaphragm C². One of these cups C' fits over the end of the wooden section A', and may be secured thereto by a nail, pin, or screw, c. Driven or screwed into the said lower end of the section A' is the screw-stud D. To couple the sections A and A' it is simply necessary to screw the stud D into the metallic socket-piece E in the end of handle A until the end is received in the cup C' and is brought up against the diaphragm C². The interior faces of cups C' should be slightly tapered, so that the ends of the sections A A' shall fit tightly therein. This coupling B is very rigid and strong, does not admit of splitting or injury to the wood, and is readily coupled and uncoupled as desired.

F is a plate to which the brush G is secured, and is provided with an obliquely and upwardly extending screw-threaded stud, D', 95 preferably formed of a wrought-iron rod cast in the plate F, the metal thereof forming an oblique seat, f, from which said stud projects. The lower end of the handle A has driven into it a screw-threaded socket-piece, E', for the reception of stud D', which socket-piece is similar to that shown in the coupling B. The end is also inclosed by a ferrule or cup-shaped piece, the cup C³ and end C⁴ thereof being

similar to that shown at C, except that it is made single instead of double, and the part C' prevents the socket-piece E' being withdrawn, for it wedges in the lower part of the 5 wooden handle, causing it to tightly grip the socket-piece, and the screw *c* holds the ferrule firm and prevents any possibility of the socket-piece being pulled out. This ferrule has a hole in its end sufficiently large to pass 10 over the stud D', and if desired it may be cast solid with the socket-piece E'. The handle is therefore readily connected to or disconnected from the brush and its plate F by screwing the handle upon the stud D', as shown, 15 and the stud and socket-piece being long, great strength and durability result, and the connection in appearance is ornamental.

The plate F is used when the brush is to be placed at an angle to the handle; but when it 20 is to be placed parallel therewith then a plate such as shown at F' in Fig. 5 may be used.

Any form of plate may be used, dependent upon the article or object to be held, and if desired the plate may be dispensed with and 25

the stud D' connect directly with the object 25 to be held, such as in the case of the soldering-iron, illustrated in Fig. 6, or other tool.

Having now described my invention, what I claim as new, and desire to secure by Letters Patent, is—

The iron holding-plate F, having a screw-threaded stud, D', and a shoulder, *f*, in combination with a handle, A, having a metallic screw-threaded socket-piece, E', in its end, the same being driven into a hole made to receive it, and adapted to receive the screw-stud D', and a metallic ferrule, C', having the part C' fitting over the end of the handle, holding the socket-piece E' in place and forming a face to jam against the face *f*, substantially as shown and for the purpose specified. 35

In testimony of which invention I hereunto set my hand.

CHARLES DONAGHY.
